Primary Examiner—Stella M Reid*Assistant Examiner*—Rashida C McCoy(74) *Attorney, Agent, or Firm*—Lawrence G. Fridman(57) **CLAIM**

The ornamental design for a shoe tree, as shown and described.

DESCRIPTION

FIG. 1: is a perspective view showing a shoe tree according to our new design;

FIG. 2: is a top plan view thereof;

FIG. 3: is a bottom plan view thereof;

FIG. 4: is a rear elevational view thereof;

FIG. 5: is a front elevational view thereof;

FIG. 6: is a right-hand side elevational view thereof; and,

FIG. 7: is a left-hand side elevational view thereof.

The broken line showing of split toe portion is included for the purpose of illustrating environmental structure and forms no part of the claimed design.
